WINDOW SHADE FIXTURE.
APPLICATION FILED DEC. 9, 1905.

UNITED STATES PATENT OFFICE.

DANIEL G. MUNDAY, OF McADOO, PENNSYLVANIA.

WINDOW-SHADE FIXTURE.

No. 825,926.

Specification of Letters Patent.

Patented July 17, 1906.

Application filed December 9, 1905. Serial No. 291,145.

To all whom it may concern:

Be it known that I, DANIEL G. MUNDAY, a citizen of the United States, residing at McAdoo, in the county of Schuylkill and State of Pennsylvania, have invented a new and useful Window-Shade Fixture, of which the following is a specification.

The invention relates to improvements in window-shade fixtures.

10 The object of the present invention is to improve the construction of window-shade fixtures and to provide an exceedingly simple and inexpensive fixture of great strength and durability adapted to be quickly applied to a window without employing screws, nails, or similar fastening devices and without marring or otherwise disfiguring the wood-work.

20 A further object of the invention is to provide a window-shade fixture of this character capable of ready adjustment to adapt it to windows of different widths and adapted also after being applied to a window and without being removed therefrom to be adjusted to fit 25 curtains or shades of different widths.

With these and other objects in view the invention consists in the construction and novel combination and arrangement of parts hereinafter fully described, illustrated in the 30 accompanying drawings, and pointed out in the claims hereto appended, it being understood that various changes in the form, proportion, size, and minor details of construction within the scope of the claims may be 35 resorted to without departing from the spirit or sacrificing any of the advantages of the invention.

In the drawings, Figure 1 is an elevation of a window-shade fixture constructed in accordance with this invention and shown applied to the upper portion of a window. Fig. 2 is a horizontal sectional view of one end of the fixture, illustrating the manner of mounting the fixed jaw. Fig. 3 is a similar view of 45 the other end of the fixture, illustrating the manner of adjusting the movable jaw. Fig. 4 is a horizontal sectional view of the central portion of the fixture, illustrating the manner of adjustably connecting the two sections or 50 members of the hanger-bar. Fig. 5 is a vertical sectional view on the line 5 5 of Fig. 1. Fig. 6 is a similar view on the line 6 6 of Fig. 1. Fig. 7 is a vertical sectional view on the

line 7 7 of Fig. 1. Fig. 8 is a detail perspective view of the adjustable jaw. Fig. 9 is a detail perspective view of one of the adjustable bearing-brackets, the spring-actuated locking-lever being removed. Fig. 10 is a rear elevation of the fixture.

Like numerals of reference designate corresponding parts in all the figures of the drawings.

The window-shade fixture is provided with fixed and movable jaws 1 and 2, adapted to engage a window-frame 3^a, at opposite sides thereof, and connected by a hanger-bar which is composed of adjustable sections 3 and 4, adapted to be moved inward and outward to vary the length of the hanger-bar to adapt the window-shade fixture for windows of different widths. The fixed jaw is provided with an attachment plate or shank 5, and the engaging portion extends from the outer end of the plate or shank 5 and is provided with a pair of spurs or projections 6, which are embedded in the window-frame, at the side edge thereof, when the fixture is applied, whereby the fixture will be securely attached to the window-frame. The attachment-plate is secured by rivets or other suitable fastening devices to the inner or rear face of the section 3 of the hanger-bar.

The adjustable jaw, which has a pair of spurs or projections 7 at its engaging portion, is provided with a plate or shank 8, which is 85 slidable on the inner or rear face of the member 4 of the hanger-bar and which is adapted to be moved inward by the means hereinafter described to force the projections or spurs 6 and 7 of both jaws into the frame of the window. The outer portion of the plate or shank is provided with a longitudinal slot 9, through which passes a headed pin or rivet 10, which engages the rear face of the plate or shank. The inner end of the plate or shank is provided with a pin or stud 11, which works in a slot 12 and which is connected to the outer end of a bar or member 13. The inner end of the bar or member 13 is connected with a combined operating and locking lever 14, composed of long and short arms arranged at an angle to each other. The locking-lever, which is fulcrumed at its angle and at an intermediate point on the hanger-bar by a pin or rivet 15, has its short arm connected to the inner end of the bar or member 13, and the

long arm is adapted to be swung upward and downward to move the short arm inward and outward, whereby the adjustable jaw is carried into and out of engagement with the window-frame. The sections 3 and 4 of the hanger-bar are preferably constructed of wood, and the section 4 is reinforced at the pivotal point of the locking-lever by a cuff 16; but the section of the hanger-bar may be constructed of any other suitable material, as will be readily understood. The outer end of the locking-lever is provided with a projecting portion or lip 17, and it has an engaging arm 18, which is adapted to interlock with the lower edge of the connecting-bar 13, whereby the lever is locked against upward movement. The engaging arm or portion 18 of the locking-lever has its terminals bent to form a substantially L-shaped flange or jaw 19, which is arranged at the lower edge and rear face of the connecting-bar when the parts are interlocked, as clearly illustrated in Fig. 7 of the drawings.

The hanger-bar is capable of ready adjustment to adapt it to windows of different widths, and the section 3 is provided with a metallic sleeve 20, into which the inner end of the section 4 telescopes. The sleeve, which is constructed of sheet metal or other suitable material, preferably consists of a front wall or portion and upper and lower substantially L-shaped flanges, which form a guide or way for the inner end of the section 4. The section 4 has its inner end reinforced by a plate 21, which is provided at suitable intervals with perforations 22, adapted to receive a projection or pin 23 of a spring-actuated locking lever or dog 24. The locking lever or dog 24 is fulcrumed at an intermediate point by a pivot or pintle 25, and the pin or projection 23 extends from one end of the dog or lever and passes through a perforation of the sleeve 20 and engages one of the perforations of the section 4. The pivot or pintle is arranged in eyes 25^a and 26 of the sleeve and the lever or dog, the eyes 25^a being formed integral with the sleeve by partially-severed portions of the front wall and rolling the partially-severed portions, as shown. The eyes of the dog or lever are located at opposite sides of the center of the same and consist of projecting portions perforated to receive the pivot or pintle. The dog or lever is maintained in its engaging position by means of a spring 27, extending longitudinally of the inner face of the said dog or lever and preferably secured to the same by the pin or projection, which constitutes a rivet. The free end of the spring is spaced from the adjacent end or handle portion of the dog or lever and bears against the sleeve, as clearly shown in Fig. 4.

In applying the fixture to a window, it is first adjusted to arrange the jaws the proper

distance apart to receive between them the 65 window-frame and to position the points or engaging ends of the spurs or projections contiguous to the side edges of the said window-frame. The movement of the adjustable jaw is sufficient to embed the spurs or projections 70 of both of the jaws in the side edges of the window-frame. By this construction the window-shade fixture may be instantly applied to a window-frame without employing screws, nail, or similar fastening devices, 75 and when the spurs or projections are embedded in the sides of the window-frame the fixture will be firmly held in position, so that there will be no liability of its becoming accidentally loosened through the use of a curtain 80 or shade having a spring-roller.

The fixture is provided at the ends of the hanger-bar with adjustable brackets 28 and 29, having openings 30 and 31 for the reception of the journals of a spring-roller, the 85 opening 30 being round to receive the round journal and the other opening being polygonal and having a slot or entrance to permit the journal which is connected with the spring of the roller to be readily introduced 90 into and removed from it. However, as the brackets are adjustable on the hanger-bar, as hereinafter explained, the entrance slot or opening is unnecessary, as the bracket may be moved inward and outward to engage it 95 with and disengage it from the journal. By employing the usual entrance slot a curtain or shade may be placed in the fixture and removed therefrom without any adjustment of the parts. Each bearing-bracket is provided with a slide 32, arranged on the hanger-bar and consisting of a sleeve having a front wall and upper and lower L-shaped flanges for engaging the upper and lower edges of the hanger-bar, the plates or shanks of the 100 fixed and movable jaws being of a width less than the width of the hanger-bar to permit the L-shaped flanges to extend a short distance inward toward each other on the rear face of the said hanger-bar. Each section of the hanger-bar is provided with a plurality of perforations 33, arranged at intervals and adapted to be engaged by a pin or projection 105 34 of a dog or lever 35 of substantially the same construction as the dog or lever 24. 110 The dog or lever 35 is mounted on the sleeve of the bracket by means of a vertical pivot or pintle 36, arranged in eyes 37 and 38 of the slide and the dog or lever. The eyes 37 of the slide are formed by rolling partially-severed portions of the front wall, and the dog or lever is held in its engaging position by a 115 spring 39, secured to the inner end of the dog or lever by the pin or projection 34. The outer end of the dog or lever extends through 120 a slot or opening 39 of the outwardly-projecting portion of the bracket to enable the latter to be adjusted from the exterior. Also

when a curtain or shade is applied to the fixture all of the locking devices are entirely concealed from view, with the exception of the outer ends of the dogs or levers of the brackets.

Having thus fully described my invention, what I claim as new, and desire to secure by Letters Patent, is—

1. A window-shade fixture, comprising a hanger-bar, a fixed jaw arranged at one end of the hanger-bar, a movable jaw located at the other end of the hanger-bar, a connecting-bar pivoted at one end to the movable jaw, and a combined operating and locking lever fulcrumed at an intermediate point on the hanger-bar and pivoted at one end to the connecting-bar and provided at its other end with means for engaging the connecting-bar at a point between the ends thereof, whereby at 15 the movable jaw is locked rigid with the hanger.

2. A window-shade fixture, comprising a hanger-bar provided near one end with a slot, a fixed jaw mounted on the hanger-bar at 25 the other end thereof, a movable jaw provided with a slot and having a stud or projection operating in the slot of the hanger-bar, a fixed stud or projection mounted on the hanger-bar and arranged in the slot of the adjustable jaw, an operating-lever fulcrumed on the hanger-bar, and connecting 30 means between the operating-lever and the stud or projection of the movable jaw.

3. A window-shade fixture, comprising a hanger-bar provided near one end with a slot, a fixed jaw mounted on the hanger-bar at the other end thereof, a movable jaw provided with a slot and having a stud or projection operating in the slot of the hanger-bar, a fixed stud or projection mounted on 40 the hanger-bar and arranged in the slot of the adjustable jaw, an operating-lever fulcrumed on the hanger-bar, a bar connecting the lever on the hanger-bar, a bar connecting the lever with the stud or projection of the movable 45 jaw, and locking means carried by the lever for engaging the connecting-bar.

4. In a window-shade fixture, the combination of a hanger-bar, a movable jaw mounted on the hanger-bar at the rear face thereof, a connecting-bar arranged at the 50 front face of the hanger-bar and connected at one end with the movable jaw, and a combined operating and locking lever fulcrumed on the hanger-bar and having a short arm

pivoted to the connecting-bar, said lever being also provided with a long arm having a projecting portion provided with means for engaging one edge of the connecting-bar. 55

5. A window-shade fixture, comprising a hanger-bar composed of two adjustable sections, a sleeve mounted on one section and slidably receiving the other section, a spring-actuated locking-lever mounted on the sleeve and provided with a pin or projection extending through the sleeve and engaging the section which slides therein, bearings carried by the sections, a fixed jaw mounted on one of the sections of the hanger-bar, a movable jaw mounted on the other section thereof, and means for adjusting the movable jaw independent of the adjustment of the sections of the hanger-bar. 65

6. A window-shade fixture provided with an adjustable bracket consisting of a slide, and a projecting portion extending from the outer end of the slide, said projecting portion having a bearing and provided with an opening, and a locking device mounted on the slide and having an operating portion extending through the said opening, said locking 80 device being also provided with means for securing the bracket in its adjustment. 75

7. In a window-shade fixture, the combination of an adjustable bracket composed of a projecting bearing portion having an opening, and a slide extending inward from the opening, and a spring-actuated locking-lever mounted on the slide and having an operating portion extending through the said opening. 85

8. In a window-shade fixture, the combination of a hanger-bar, a jaw arranged on the inner face of the hanger-bar and provided with a shank or plate of a width less than the hanger-bar, and an adjustable bearing-bracket having a slide, said slide being provided with upper and lower substantially L-shaped flanges engaging the upper and lower edges of the hanger-bar, and means carried by the slide for engaging the hanger-bar. 95

In testimony that I claim the foregoing as my own I have hereto affixed my signature in the presence of two witnesses.

DANIEL G. MUNDAY.
